CLAIM

The ornamental design for a television receiver, as shown and described.

DESCRIPTION

1. Television receiver

1.1 is a front elevation view of a television receiver showing our new design;

1.2 is a rear elevation view thereof;

1.3 is a left side elevation view thereof;

1.4 is a right side elevation view thereof;

1.5 is a top plan view thereof;

1.6 is a bottom plan view thereof; and

1.7 is a perspective view thereof.

The broken lines in the drawings illustrate portions of the television receiver that form no part of the claimed design.
